BIRD CAGE

Donald R. Reachtet, North Hollywood, Calif.

Application June 28, 1955, Serial No. 36,737

Term of patent 14 years

(Cl. D31—2)

FIG. 1.

FIG. 2.

FIG. 3.

Figure 1 is a perspective view of a bird cage embodying my new design;

Figure 2 is an enlarged side elevational view of the bird cage illustrated in Figure 1; and

Figure 3 is a bottom view looking upwardly at the showing of Figure 2.

I claim:

The ornamental design for a bird cage, as shown.
